UNITED STATES PATENT OFFICE.

HOWARD PAUL CULVER, OF PARKERSBURG, WEST VIRGINIA, ASSIGNOR OF ONE-HALF
TO J. H. RANDOLPH, OF PARKERSBURG, WEST VIRGINIA.

REFRIGERATING APPARATUS.

Application filed April 29, 1924. Serial No. 709,731.

To all whom it may concern:

Be it known that I, HOWARD PAUL CULVER, a citizen of the United States, and a resident of Parkersburg, in the county of 5 Wood and State of West Virginia, have invented certain new and useful Improvements in Refrigerating Apparatus, of which the following is a specification.

This invention relates to refrigerating apparatus, and is more particularly directed 10 to a unitary structure for compressing gases employed in refrigeration.

An object of the invention is the provision of a simple, compact and unitary structure comprising a compressor embodied in a casting which includes the coils that carry the compressed gases and operating mechanism for the compressor.

Another object of the invention is the 20 provision of a casting enclosing a compressor and in which leaf valves are employed for controlling the flow of gas to be compressed through the pistons to the compression cylinders and for controlling the discharge of the compressed gas through the cylinder heads.

A further object of the invention is the provision of a casting including compressor cylinders and a crank case for the driving 30 shaft of the compressors which is partially filled with oil, with valves in the piston and cylinder head for controlling respectively the admission and discharge of the gases to the compressor, and a chamber located beyond the cylinder head adapted to receive oil from the crank case to provide an oil seal between the compressor cylinder and the pipe line carrying the compressed gas to prevent return of the compressed gases to the compressor cylinders.

A still further object of the invention is the provision of a double acting compressor in which the gases are alternately compressed for supplying with compressed 45 gases a self-contained chamber in a casting which includes the compressor cylinders, crank case and water jacket for the compressor cylinders.

Another object of the invention is the provision of a hollow casting in which are integrally incorporated the compressor cylinders and crank case isolated from the remaining portion of the chamber in the casting which forms a cooling jacket for the crank case and cylinders, with coils

carrying the compressed gases from the compressor cylinders immersed in the cooling water so that the temperature of the gases and compressor cylinders are sufficiently reduced for an efficient and economical production of a refrigerating medium. 60

A still further object of the invention is the provision of a casting forming a unitary structure including a pair of oppositely disposed compressor cylinders with pistons 65 working in said cylinders and a casting integrally and interiorly formed of the main casting providing a crank case to which the evaporated gases after having accomplished their work in the refrigerating plant are directed, the gases entering angularly disposed passages through the pistons to the compressor cylinders, with a leaf valve preventing return of the gases 70 during compression. 75

This invention will be best understood from a consideration of the following detailed description, in view of the accompanying drawings forming a part of the specification; nevertheless it is to be understood that the invention is not confined to the disclosure, being susceptible of such changes and modifications which shall define no material departure from the salient 80 features of the invention as expressed in the 85 appended claims.

In the drawings:

Figure 1 is a side elevation of the compressor unit partly in section.

Figure 2 is a top plan view of the compressor unit with parts broken away to disclose the interior construction. 90

Figure 3 is an end view in elevation of the compressor unit partly in section.

Figure 4 is a plan view of a disc located 95 at the end of each compressor cylinder.

Figure 5 is a sectional view of the disc shown in Figure 4 with a cooperating valve.

Figure 6 is an enlarged section of a compressor piston. 100

Figure 7 is an end view of a piston.

Referring more particularly to the drawings, 1 designates a casting forming the housing for the compressor, the coils carrying the compressed gases and the cooling water for the compressor so that the device forms a compact and unitary structure. The top of the casting is open and provided with a peripheral flange 2 having threaded 105 passages adapted to receive bolts 3 which 110

have their heads countersunk in a cover plate 4.

The cover plate is provided with bosses 5 having threaded passages to receive the bolts 6 which lock a motor base plate 7 to the cover plate. The base plate carries a motor 8 having a twin groove pulley 9 for driving the shaft which operates the compressor piston.

10 The casting 1 is provided with a water chamber 10 which embraces substantially all of the interior of the casting except the integrally formed castings providing a crank case 11 and compressor cylinders 12 and 13. A partition 14 spaced from the base 15 of the casting provides a chamber 16 below the water chamber 10 for storing the compressed gases which are in liquid form before they are directed to the 20 refrigerating plant.

The ends of the casting adjacent the heads of the cylinders 12 and 13 are provided with circular openings which are closed by cover plates 17. A cylinder head 18 is secured by means of bolts 19 to an annular flange 20 projecting laterally from the ends of the cylinders 12 or 13 and the cover plates 17 are provided with a perforated boss 21 adapted to receive a threaded screw 22 having its inner end screwed into a threaded passage in a boss 23 on the cylinder head 18 and a nut 24 locks the plate 17 to an end wall of the casting 1 which has an annular rib 25 engaged by an annular flange 26 on the closure plates 17. By removal of the screw 22 and bolts 19 the cylinder heads 18 may be removed and the discharging valves of the compression cylinders may be inspected, renewed or repaired 40 when desired or necessary.

The casting 11 is formed integrally with the partition 14 and the casting 1 and has one end open as shown in Figure 3 and is closed by a cap or plate 27. The inner side wall of the casting 1 is provided with internally threaded bosses 28 which are adapted to receive the bolts 29. Nuts 30 on the bolts 29 lock the plate 27 to the outer face of the casting 1. The inner wall of the plate 27 is provided with an annular flange 31 forming a shoulder which is adapted to engage the inner periphery of the opening in the side wall of the casting. Integrally formed with the cover plate 27 is a bearing 32 which extends axially of the plate and in line with the axis of the substantially circular casting 11 forming the crank case of the driving mechanism.

60 The inner end of the bearing 32 where the same projects into the crank case 11 is provided with an enlarged bore as shown at 33 to receive a ball bearing 34 which is mounted on the inner end of a drive shaft 35. Between the bore 36 of the bearing 32 and the shaft 35 are placed a plural-

ity of metallic and non-metallic washers which form an absolute seal to prevent the loss of lubricating oil past the bearing 32. A spring 37 embracing the shaft 35 has its inner end in engagement with the outer 70 brass washer 38 while its other end is adapted to engage a washer 39 abutting a second ball bearing 40 located on the outer end of the shaft 35 and held in place by a lock nut 41 which engages threads on the shaft 35. 75

A flanged ring 42 which is screwed to an annular boss 43 on the end wall of a housing 44 is adapted to cooperate with the nut 41 for maintaining the bearing in position. A gland 45 engages the internal threads of 80 the sleeve or ring 42. A disc fly wheel 46 is secured upon the outer free end of the shaft 35 and is provided with a pair of grooves 46^a which are similar in cross section to the grooves 9^a of the pulley 9 on the motor 8. 85 V-shaped belts are entrained over the pulley 9 and the fly wheel 46.

The housing 44 forms an extension of the cap plate 27 and is provided with a cover 47 at its upper end. A plug 48 is threaded into an opening in the lower end of the housing 24.

Upon the inner threaded end 49 of the shaft 35 is screwed a driving disc 50 having 95 an eccentric or crank pin 51 screwed into a threaded perforation transversely of the disc and projecting sufficiently beyond said disc to receive a ball bearing roller 52 which is adapted to be received within a yoke 53, formed by the connected ends of the piston rods 54 and 55. Rotation of the roller 52 around the center of the shaft 35 reciprocates the piston rods 54 and 55 in a horizontal manner. The abutting forked ends of the piston rods are connected together by means of bolts 56. A piston 57 is integrally formed at the end of each piston rod 54 and 55 and is provided with a plurality of 100 passages 58 extending from the rear end 59 of the piston through the working face as shown at 60. These passages are extended through the piston 57 at an acute angle to the axis of said piston, with the outer ends of the passages being in a line adjacent the 105 axis of the piston rod 54.

A narrow reed valve 61 rectangular in shape is secured at one end by means of a bolt 62 while its other end is maintained against vibration by a bolt 63. Said valve extends across the openings 60 of the passages 58 and maintains the same closed during the compression stroke of the piston. The outer flanged ends 20 of the compression cylinders 12 are provided with a groove 110 in which is adapted to be seated an annular flange 65 projecting inwardly from the cylinder head 18. By forming the groove 64 an annular shoulder 66 is provided and with its outer ends machined to receive a disc 67. 115 This disc is provided with two openings 68

at diametrically opposite points and are closed by an annular disc or valve 69 which is circular in formation and formed of thin sheet spring steel. The valve 69 is secured 5 to the disc 67 by means of a screw 70. A spring 71 engaging the inner wall 72 of a chamber 73 formed in the cylinder head 18 embraces the head of the screw 70 and engages the valve 69 and maintains the disc 67 10 in engagement with the annular flange 66 on the end of the cylinder 12 or 13. The disc 67 is provided with notches 74 at diametrically opposite points on said disc adapted to receive pins 75 which project 15 laterally from the flange or rib 66 on the end of the compression cylinder 12. The pins engaging the notches 74 prevent rotation of the disc 67. The heads of the bolts 62 and 63 are of such a character that when 20 the compression pistons 57 are moved to the end of their working stroke said heads will enter the perforations 68 in the disc 67 in order to permit compression pistons to be moved in close association with the disc 67. 25 The upper ends of the cylinder heads 18 are provided with internally threaded passages in communication with a passage 76 which forms a discharge port for the chamber 73 which is filled with oil during the 30 normal operation of the compressor. A nipple 78 is screwed into the threaded opening in the cylinder head 18 and is connected to a discharge pipe 79 by means of a gland 80. Cylinder 12 is connected by means of a 35 discharge pipe 79 with a cross head 81 while cylinder 13 is connected by means of a pipe 82 to said cross head whereby the compressed gas which is now being cooled is forced through the cross head and which is then discharged through a plurality of 40 coils of pipes 84 and 85. These pipes are formed into coils at the upper ends of the water chamber 10, the coils being connected at their lower ends to a cross head 86, which 45 is connected by a cored rib 86^a to chamber 16 integrally formed with the casting 1. This chamber is adapted to form a storage 50 tank for the compressed or liquid gases before they are directed to the refrigerating plant connected with the compressor. A valve cage 87 is threaded into an opening 88 in the end wall of the lower end of the casting 1 and is provided with a screen 89 projecting into the storage chamber 16. 55 The cage 87 is provided with a valve seat 90 adapted to be engaged by a valve 91. A port 92 formed in the valve cage 82 is provided with connections 93 which are directed to the refrigerating plant. A stem 94 of 60 the valve 91 has a threaded enlarged portion 95 screwed to a threaded portion in the bore 96 of the valve cage. The outer end of the valve stem 94, as shown at 97 is provided with a rectangular portion adapted 65 to be engaged by some suitable tool for op- erating the valve to closed or open position. A threaded cap or plug 98 is screwed into the internally threaded open end of the valve cage 87, and is adapted to seal the cage against the loss of fluid. When it is 70 desired to operate the valve 91 the cap screw 98 is removed and a suitable socket wrench is inserted within the bore of the valve cage and engages the rectangular end 97 of the stem 94 of the valve. 75

The casting 1 within the water chamber 10 is provided with a rib 99 which is bored, as shown at 100 to form a passage for the return of the evaporated gases through an opening 101 in the casting 11 of the crank case so that the exhausted gases are returned to the crank case to be compressed in the compression chamber 102 of the compression cylinders 12 and 13. 80

A valve cage 103 has a threaded end 85 screwed into a threaded portion of the passage 100 where said passage opens to the end wall of the casting 1. The cage is provided with a valve seat 104 engaged by a valve 105. This valve is provided with 90 a stem 106 located in a bore 103 and is operated in a manner similar to the operation of the valve stem 94 of the valve cage 87. A cap nut 107 closes the outer open end of the cage 103 and when removed the end of 95 the valve stem may be engaged by a socket wrench for operating the same. The valve cage 103 has an extension, as shown at 108, to which is connected a pipe line 109 which is connected with the exhaust end of the 100 refrigerating plant and through a passage 110 in the needle 109, the exhausted gas enters through the valve cage past valve 105 into the passage 100 and to the crank case 11. 105

It is essential in operating a compressor for refrigerating machines that the temperature of the compressor pistons and of the gas to be compressed be maintained at a low degree so that the gases will be readily compressed and forced from the compression chamber of the cylinder. Otherwise if any gas remained in the compression cylinders, the gas would expand upon a vacuum being created in the compression chamber and react to prevent the inflow of gases to the compression chamber past the usual valves for the purpose. It will be seen that in the present construction that the working face of the pistons 57 move at the completion of 110 its work stroke in close contact with the disc 67 thereby forcing all of the compressed gases past the disc 67 and through the opening 69 in said disc and through the chamber 73 and into either of the pipes 79 115 or 82 to the cross head 81. This is made possible by the fact that the heads of the bolts 62 and 63 enter the respective perforations 68 in the disc 67. 120

The oil in the crank case 11 as shown at 130

a predetermined level and is substantially maintained at this level by fresh supplies at various times. As this oil is splashed over the connecting rod 54 and into the 5 compression cylinders 12 and 13 the oil is carried through the passages 58 past the leaf valve 61 and into the compression chambers 102 of said cylinders. This oil is forced with the compressed gases into the 10 chamber 73 and after a certain length of time chamber 73 will be substantially filled with oil and as the compressed gases are forced into said chamber they pass through the oil and into the respective outlet pipes 79 and 82. The oil filling in the chamber 15 73 acts as a seal and prevents the loss of fluid such as the compressed gas. The gases pass up through the oil in the chamber 73 and some of the oil is forced upwardly with the gas, but such oil drains back into the chamber so that sufficient oil is retained in the chamber with the gas acting against the volume of oil.

The spent or evaporated gases passing 25 through the passage 100 enter the crank case and carry some of the oil through the passages 58 into the compression chambers. Since the pistons act in opposite directions the gas from the crank case 11 will enter 30 one compression chamber upon the suction stroke while the compressed gases are being forced past respective valves in its cylinder head through the discharge pipes and into the coils 84 and 85 where they are finally 35 stored in the chamber 16. Some of the oil is carried through the coils and into the chamber 16 and out with the liquid gas to the refrigerating plant where it is recovered in a manner which is well known in 40 the art.

The screen 89 prevents foreign matter from being carried from the chamber 16 through the leads directed to the refrigerating plant.

45 It will be seen that from the construction, a self-contained compressor unit is formed and combined within a single casting which includes the crank case, compressor cylinder and a storage chamber for the liquid gases. The interior of the casting 1 forms a water 50 jacket for the cylinders 12, 13 and the crank case 11, the interiors of which being isolated from the water jacket. As shown at 111 the cylinders 12 and 13 are spaced above 55 the floor 14 of the water chamber so that the water may circulate all around the cylinders and the cylinder heads. Furthermore the coils 84 and 85 which carry the compressed gases to the storage chamber 16 60 are located above the compression cylinders and crank case and are likewise embraced by the water of the jacket.

The motor 8 has its base plate secured to the removable top of the casting 1 so that 65 the motor, together with the casting, like-

wise forms a compact and unitary structure.

The cooling chamber of the casting 1 is provided with an inlet opening 112 which is adapted to be connected in the usual manner with a water system of the community while an opening 113 is adapted to be connected with a pipe for permitting the warmer areas of the water to escape to the usual sewerage system. The cooling of the compressed gases in the coils 84 and 85 by the water together with the pressure upon the gases from the cylinders 12 and 13 condenses the liquid before the liquid enters the chamber 16.

If at any time liquid escapes through passages 58 to the compression cylinders the liquids are forced past discs 67 which are raised from their seats thus permitting the escape of the liquid without injury to the cylinder heads.

Non-metallic packing rings 114 and 115 are located in the bore 26 on shaft 35. A spacing ring 117 separates rings 114 from rings 115. A babbitt washer 116 located at 90 the extreme inner end of the bore 36 and in engagement with an adjacent shoulder on the shaft 35 and bore 36 seals the bore from oil leakage.

Perforated lugs 120 and 121 projecting 95 from the bottom 15 of the casting 1 are for the purpose of securing the unit to a fixed support.

What I claim is:

1. A refrigerating compressor condenser 100 unit comprising a casting, a partition dividing the casting into a chamber for storing condensed gas and a chamber for cooling water, a crank case integrally formed with the casting in the cooling chamber, a pair 105 of oppositely disposed compressor cylinders cast integrally with the crank case and supported above the partition in the cooling chamber by the crank case.

2. A refrigerating compressor condenser 110 unit comprising a casting, a partition dividing the casting into a chamber for storing condensed gas and a chamber for cooling water, a crank case integrally formed with the casting in the cooling chamber, a pair 115 of oppositely disposed compressor cylinders cast integrally with the crank case, and cylinder heads removably connected with the outer ends of the compression cylinders, said casting being provided with openings in 120 alignment with the cylinder heads.

3. A refrigerating compressor unit comprising a casting, a partition dividing the casting into a chamber for storing condensed gas and a chamber for cooling water, 125 a crank case integrally formed with the casting in the cooling chamber, a pair of oppositely disposed compressor cylinders cast integrally with the crank case, cylinder heads connected with the outer ends of the 130

compression cylinders, and provided with chambers, valves between the cylinders and the chambers, said chambers being adapted to be filled with oil to form a seal, a condensing coil in the cooling chamber connected with the chamber for storing condensed gases and vertically disposed pipes forming a connection between the coil and the oil chamber in the cylinder head whereby oil which is forced towards the cooling coil will readily drain back to the oil chambers.

4. A refrigerating compressor condenser unit comprising a casting, a partition dividing the casting into a chamber for storing condensed gas and a chamber for cooling water, a crank case integrally formed with the casting in the cooling chamber, a pair of oppositely disposed compressor cylinders cast integrally with the crank case, cylinder heads removably connected with the outer ends of the compression cylinders, the opposite ends of the casting being provided with openings and closures removably connected with the cylinder heads.

5. A refrigerating compressor condenser unit comprising a casting, a partition dividing the casting into a chamber for storing condensed gas and a chamber for cooling water, a crank case integrally formed with the casting in the cooling chamber, a pair of oppositely disposed compressor cylinders cast integrally with the crank case, cylinder heads removably connected with the outer ends of the compression cylinders, a piston mounted for reciprocation in each cylinder, means for driving the piston, said pistons provided with passages connecting the crank case with the compression chamber in the cylinder and a valve on the working face of each piston for controlling the passages.

6. A refrigerating compressor unit comprising a casting, a partition dividing the casting into a chamber for storing condensed gas and a chamber for cooling water, a crank case in the cooling chamber, a pair of oppositely disposed compressor cylinders connected by the crank case, cylinder heads provided with oil chambers, valves separating the chamber in the cylinder head from the compression cylinders, said chambers being adapted to be filled with oil to form a seal, pistons movable in the compression cylinders, means for operating the pistons, coils in the cooling chamber connected with the chambers in the cylinder heads, said coils being connected with the storage chamber for condensed gases, said coil being disposed above the cylinders, the connections between the chambers in the cylinder heads and the coils being vertically disposed whereby oil forced through said connections toward the coils will drain back into the chambers in the cylinder heads.

7. A refrigerating compressor unit comprising a casting, a partition dividing the casting into a chamber for storing condensed gas and a chamber for cooling water, a crank case integrally formed with the casting in the cooling chamber, a pair of oppositely disposed compressor cylinders connected by the crank case, a cylinder head provided with chambers mounted on the

prising a casting, a partition dividing the casting into a chamber for storing condensed gas and a chamber for cooling water, a crank case integrally formed with the casting in the cooling chamber, a pair of oppositely disposed compressor cylinders connected by the crank case, a cylinder head provided with a chamber connected with each compressor cylinder, cooling coils above the cylinders and crank case in the cooling chamber, a cross head connected with the upper end of the coils, and vertical conduits connecting the cross head with the chambers in the cylinder head, the lower ends of the coils being connected with the chamber for storing compressed gas, said vertical conduit providing drains to permit oil which has been forced upwardly toward the coils to drain back into the chambers in the cylinder heads.

8. A refrigerating compressor unit comprising a casting, a partition dividing the casting into a chamber for storing condensed gas and a chamber for cooling water, a crank case integrally formed with the casting in the cooling chamber, a pair of oppositely disposed compressor cylinders connected by the crank case, cylinder heads provided with chambers mounted on the compressor cylinders, a valve between the chamber in the cylinder head and each compressor cylinder, a piston operatively mounted in each compressor cylinder, a plurality of coils mounted above the crank case and the cylinders, a cross head connected with the upper ends of the coils, conduits connecting the chambers in the cylinder head with the cross head, a cross head connected with the lower end of the coils, a conduit connecting said cross head with the chamber for storing condensed gases, the cooling chamber adapted to be supplied with a cooling liquid which completely embraces the compressor cylinder, cylinder heads, crank case and coils.

9. A refrigerating compressor condenser unit comprising a casting, a partition formed integrally with the casting and dividing said casting into a chamber for storing condensed gases and a chamber for cooling water, a crank case integrally formed with the casting in the cooling chamber, a pair of oppositely disposed compressor cylinders integrally formed with the crank case in spaced relation with the walls of the cooling chamber.

10. A refrigerating compressor unit comprising a casting, a partition dividing the casting into the chamber for storing condensed gas and a chamber for cooling water, a crank case integrally formed with the casting in the cooling chamber, a pair of oppositely disposed compressor cylinders connected by the crank case, a cylinder head provided with chambers mounted on the

6
compressor cylinder, a valve between the chamber in the cylinder head and the compressor cylinder, a piston operatively mounted in each compressor cylinder, a plurality of coils mounted above the crank case and the cylinders, a cross head connected with the upper end of the coils, a second cross head connected with the lower end of the coils, vertically disposed pipes connect-

ing the first mentioned cross head with the 10 chambers in the cylinder head, a rib formed integrally with the inner wall of the casting and provided with a longitudinal bore in communication with the storage chamber and means connecting the other end of the 15 bore with the second mentioned cross head.

HOWARD PAUL CULVER.
